BY Victor J. Evans, ATTORNEY

UNITED STATES PATENT OFFICE

HENRY C. W. JOHNSON, OF PASADENA, CALIFORNIA

EMERGENCY LOCK

Application filed May 25, 1928. Serial No. 280,611.

This invention relates to door locks, and its general object is to provide a protecting device for banks and the like, that not only includes means for locking doors when desired from a plurality of places remote from the doors, but also includes signalling means capable of being put into operation simultaneously with the locking operation of the door locking means.

10 A further object of the invention is to provide an emergency lock for a door, that can be operated in a manner whereby the operator cannot be detected, and the releasing means as well as the locking means is so disposed to preclude the possibility of an unauthorized person from endeavoring to unlock the door which when locked cannot be opened by force, therefore will prevent any person from leaving the premises until the door is released.

20 Another object of the invention is to provide a device of the character set forth, that is simple in construction, inexpensive to manufacture and to install and is efficient in operation and service.

25 This invention also consists in certain other features of construction and in the combination and arrangement of the several parts, to be hereinafter fully described, illustrated in the accompanying drawings and specifically 30 pointed out in the appended claims.

In describing my invention in detail, reference will be had to the accompanying drawings wherein like characters denote like or corresponding parts throughout the several 35 views, and in which:

Figure 1 is a sectional view showing parts of my invention in elevation and in normal position.

Figure 2 is a sectional view taken approximately on line 2—2 of Figure 1.

Figure 3 is a detail view illustrating the gear which forms a part of my invention and its operating rod.

Figure 4 is a similar view of the contact carrying disk.

Figure 5 is a view of the contact plate.

Figure 6 is a fragmentary sectional view taken longitudinally through the rack and showing the locking bolt of my device in side elevation.

Figure 7 is a transverse sectional view taken through the drum and showing an operating lever therefor.

Figure 8 is a perspective view of the operating rod.

Figure 9 is a sectional view taken approximately on line 9—9 of Figure 1.

Figure 10 is a diagrammatic view illustrating the lock in operative position, and the signalling system associated therewith.

Referring to the drawings in detail, the letter A indicates a door which may be of the rotating or swinging type, but in any event, the door is provided with a recess to accommodate an insert 1 of metal or like material which is provided with a bore 2 to accommodate the locking bolt 3 of my locking mechanism, as suggested in Figure 1 of the drawings. The locking bolt is shown in this figure as being in retracted or normal position.

The letter B indicates the floor of a building which as shown is concrete and arranged in the floor and extending through the same is a flanged sleeve 4 which is substantially 55 square in cross section and disposed in registration with a compartment 5 arranged in a casing 6 secured in any appropriate manner to the underside of the floor as best shown in Figure 1 of the drawings.

The casing 6 is formed with a flanged opening in one end thereof, and this opening is provided with a hinged door 7 having any appropriate latching or locking means for securing the door in its closed position as 60 shown.

Disposed in the casing adjacent the opening is an upright 8 having its ends secured to the top and bottom of the casing and formed with said upright is a bearing 9 having secured therein one end of a shaft 10 while the opposite end of the shaft is secured to one side of the casing as best shown in Figure 2. Depending from the top of the casing and secured in position through the instrumentality 65 of angle brackets 11 is a plate 12 having passed therethrough binding posts 13 which terminate in heads 14 for a purpose which will be presently apparent. Loosely mounted on the shaft 10 is a disk 15 of insulating material 70

and which has secured thereto and arranged adjacent its periphery on one side, a contact strip 16 positioned to contact the heads 14 of the binding post for wiring engagement therewith as suggested in Figure 1.

5 A gear 17 is also loosely mounted on the shaft 10 and surrounding said shaft 10 and having its end convolutions engaging the gear 17 and the upright 8 is 70 a coil spring 18 adapted for holding the disk 15 in close association with the plate 12 so that the contact strip will engage the heads upon rotation of said disk as will be apparent.

10 15 Arranged in parallelism with the shaft 10 is a shaft 19 having mounted thereon a drum 20 having secured thereto a lever which includes an arcuate portion 21 and an arm 22. The drum is provided with a recess 23 to 80 20 accommodate the hooked end 24 of a lever 25 which is pivoted intermediate its ends as at 26, and the hooked end is normally held in the recess through the instrumentality of a coil spring 27.

25 Secured to one end of the drum in any appropriate manner for movement thereby is an arm 28 which is formed with a plurality of openings 29 for the purpose of adjustably receiving one of the ends of a rod 30 which 90 30 has its opposite end passing through a slot 31 formed in the gear 17, and the last mentioned end of the rod is reduced to provide a stud 32 secured in the disk 15, as best shown in Figure 9.

35 Rising from the bottom of the casing is a bracket 33 which has secured thereto one end of a coil spring 34 while the opposite end is secured to the hooked end of the arm 22. This arm 22 has secured thereto an eye-bolt 35 which receives one end of a cable 36 100 40 trained through a sheave wheel or pulley 37 and passes through an opening 38 formed in the end of the casing as shown in Figure 1.

45 Arranged for slidable movement in the compartment 5 is a rack 39 having its teeth in mesh with the teeth of the gear 17 and the compartment is provided with a slot 40 for this purpose. The upper end of the rack 39 is formed with a bore to accommodate 50 the shank 41 of the locking bolt 3. The shank has a slot 42 arranged longitudinally therein for receiving a pin 43 secured in the bore and transversing the same, as best shown in Figure 6. The locking bolt is normally disposed in its raised position as shown 55 in Figure 6 by a coil spring 44 arranged in the bore of the rack. The locking bolt is mounted in the rack in the manner as shown and described for the purpose of locking the 60 door in the event the door should be in open position, and it will be apparent that if the bolt is arranged in its locking position as shown in Figure 10, when the door is moved to its closed position, the bolt will engage the 65 inclined wall 45 of a recess formed in the

75 insert 1 and thereby repress the bolt until the bore of said insert is disposed in registration with the sleeve, then the spring 44 will force the bolt into said bore to hold the door against movement.

Secured to one end wall of the casing by a bracket clamp 46 is a magnet 47 having its core 48 arranged in alignment with one end of the lever 25.

75 By this construction it will be seen that when the magnet is energized, it will rock the lever 25 for moving the hooked end thereof out of the recess 23 of the drum to allow the coil spring 34 to rotate the drum whereby 80 said arm 28 will be moved accordingly to pull upon the rod 30 which in turn will rotate the disk 15 and the gear 17, for disposing the contact strip 16 in engagement with the heads of the binding posts 13 and for arranging the bolt in its operative position. The bolt is 85 retracted by pulling upon the cable 36 which reverses the movement of the drum and the parts operated by the arm 28 as will be apparent.

90 In Figure 10 I have illustrated the manner of connecting a signalling system with my locking mechanism, and this system includes means for notifying the police department, as well as police and persons in the vicinity of the building in which my locking device is installed. The signalling system is adapted to be put into operation approximately simultaneously with the operation of locking a door by my locking mechanism and this system also includes indicating means for notifying persons in the building 95 that the mechanism has been operated.

100 The magnet 47 is energized for operating the locking mechanism by switches 49 which of course may be arranged at any desired place remote from the locking mechanism and any number of switches may be employed. The switches are in electrical connection with the magnet 47 and a source of 105 electrical energy 50, through the medium of a conductor 51 connected with one of said switches and to a conductor 52 which is connected with the remaining switches. The switches are connected to a conductor 53 by conductors 54, 55, and 56 and the conductor 53 is connected with a conductor 57 having one end connected with the source of energy 50 which likewise has connected thereto a conductor 58 having connection with a conductor 59 leading to and connected with the magnet to complete the circuit thereto as 110 shown.

115 The signalling system is put into operation prior to the operation of the locking bolt 3, and this feature of the device is due to the slot 31 in the gear 17, which allows the rod 30 to move the distance of the slot before it 120 operates the gear 17. However, the rod 30 will rotate the disk 15 during its movement in the slot 31, with the result the strip 16 is 130

disposed in contacting engagement with the heads 14 of the binding post 13 to close the circuit to the signalling system before the gear 17 is operated.

5 One of the binding posts 13 has electrically connected thereto the conductor 57 which as previously set forth is connected to the source of energy 50 having also connected thereto a conductor 58. In connection with the conductor 58 is an annunciator of the drop signal type and which is adapted to be disposed in a police station or the like. For the purpose of illustration, I have shown one of the dropping plates of the annunciator which is 10 indicated by the reference numeral 60. The annunciator is in electrical connection with the other binding post 13 by a conductor 61 which has connected thereto a conductor 62 leading to an audible signal such as an electric bell 63 disposed in the building equipped with my device. The bell 63 is also in electrical connection with the conductor 53 and this conductor 53 as well as the conductor 62 have in electrical connection therewith visual 15 signalling means which as shown are electric lamps 64 which is adapted to be disposed adjacent each switch whereby a person in operating the switch can see at a glance whether or not the locking mechanism has 20 been put into operation.

The switches 49 are to be secreted in such manner that the burglar or bandit will inadvertently close the particular circuit, upon the opening of a cash drawer, etc.

25 From the above description and disclosure of the drawings, it will be obvious that I have provided a combined door locking device and signalling system for the purpose of protecting banks and the like from being 30 robbed and also to trap persons attempting to rob the premises protected by my device.

It is thought from the foregoing description that the advantages and novel features of my invention will be readily apparent.

45 I desire it to be understood that I may make changes in the construction and in the combination and arrangement of the several parts, provided that such changes fall within the scope of the appended claims.

50 What I claim is:

1. In a device of the character described, a locking bolt, a rack for operating said bolt, guiding means for said rack and being provided with a slot, a shaft, a gear mounted for 55 rotation on said shaft and having its teeth passing through said slot for engagement with the teeth of said rack, a disk mounted for rotation on said shaft, a rod having one end passing through a slot arranged in said 60 gear and secured to said disk, a rotatably mounted drum, an arm carried by the drum and having secured thereto the opposite end of said rod, a lever including an arcuate shape portion secured to said drum, an arm formed 65 with said arcuate shape portion, a coil spring

for moving said drum and secured to the end of said lever, means for preventing rotation of said drum, means for operating the last mentioned means for releasing said drum, and a plate supported adjacent said disk. 70

2. In a device of the character described, a casing, a rack mounted for slidable movement in said casing, a gear for moving said rack, a locking bolt operated by said rack, means carried by a door for receiving said locking bolt, a shaft loosely receiving said gear, an insulating disk carried by said shaft, means secured to said disk and passing through a slot formed in said gear for rotating said disk, a drum, a shaft loosely receiving said drum, an arm secured to said drum and being connected to said last mentioned means, means for rotating said drum, a lever pivotally secured intermediate its ends and being adapted to prevent rotation of said drum, and a cable for resetting said drum. 80 85

In testimony whereof I affix my signature.

HENRY C. W. JOHNSON.
